UNITED STATES PATENT OFFICE.

TOM LEADBEATER, OF LEEDS, ENGLAND.

SOLE AND HEEL FOR BOOTS OR SHOES.

SPECIFICATION forming part of Letters Patent No. 680,868, dated August 20, 1901.

Application filed December 14, 1900. Serial No. 39,895. (No model.)

To all whom it may concern:

Be it known that I, TOM LEADBEATER, a subject of the Queen of Great Britain and Ireland, residing at 36 Victoria road, Leeds, England, 5 have invented new and useful Improvements in or Relating to Soles and Heels for Boots or Shoes, of which the following is a specification.

This invention relates to improvements in the soles and heels of boots and shoes; and its 10 object is so to construct or to form the sole and heel that they can at pleasure be readily placed upon or removed or detached from the main or "through," hereinafter termed the "middle," sole, to which the upper is lasted 15 or to which the lasted upper is subsequently attached as occasion requires, thus enabling several pairs of the improved soles and heels to be placed upon or removed from or worn with the uppers of a single pair of boots or 20 shoes, as well as to enable such soles and heels to be packed into small compass for the purposes of transit. I attain this object by the means illustrated in the accompanying drawings, in which—

25 Figure 1 is a part-sectional elevation of a boot with my invention applied; Fig. 2, a transverse section on line A B, Fig. 1; Fig. 3, a transverse section on line C D, Fig. 1; Fig. 4, a sectional elevation of the middle sole with 30 the upper removed therefrom; Fig. 5, a plan of same; Fig. 6, a transverse section on line E F, Fig. 5; Fig. 7, a transverse section on line G H, Fig. 5; Fig. 8, a sectional elevation of the outer sole with a longitudinal retaining-piece extending the whole of its length; Fig. 9, a plan of same; Fig. 10, a transverse section on line I J, Fig. 9; Fig. 11, a sectional elevation of the heel; Fig. 12, a plan of same; Fig. 13, a part sectional elevation of a boot 35 with my invention applied, in which the longitudinal retaining-piece is dispensed with; Fig. 14, a transverse section on line K L, Fig. 13; Fig. 15, a sectional elevation of the middle sole shown at Fig. 13; Fig. 16, a plan of 40 same; Fig. 17, a transverse section on line M N, Fig. 16; Fig. 18, a transverse section on line O P, Fig. 16; Fig. 19, a sectional elevation of the outer sole shown at Fig. 13; Fig. 20, a plan of same; Fig. 21, a transverse section on line Q R, Fig. 20; Fig. 22, a longitudinal section of the heel on line S T, Fig. 23; Fig. 23, a plan of same.

Similar characters refer to similar parts throughout the several views.

a is the upper of the boot or shoe, herein- 55 after termed and included in the term "boot;" b, the inner sole, skived on one of its surfaces from the edge inward to receive the inturned portion of the upper when lasted, as shown at Fig. 2; c, the middle sole, running, as usual, 60 the entire length of the boot; d, the welt, which in some classes of boots is sewed or otherwise fixed to one of the surfaces of the middle sole between it and the upper; e, the outer sole, and f the heel. 65

All the above-described parts with the exception of the middle and outer soles and the heel are of the ordinary construction, and the upper is lasted to the inner sole in the usual manner. 70

The middle sole c is constructed as shown at Fig. 5, in which a portion of its front edge or perimeter is removed to form a kind of recess g, extending from a point h at or near the waist on one side of the boot around the toe 75 to a point i at or near the waist on the opposite side of the boot. The shoulders at points h and i vary in depth, as shown, in order to follow the curves of the sole. A second recess j is also formed in this portion of the 80 sole between the points h and i by the removal of a portion of the newly-formed edge by cutting a rabbet, say, about one-half the thickness of the sole to form a kind of scarf-joint—that is to say, a narrow strip is cut 85 away or otherwise removed from the sole, which strip in cross-section would be, say, a square the sides of which would each be equal to about, say, one-half of the thickness of the said sole to form the recess j, thereby 90 permitting the edge k to form a ledge, and thus allowing one portion of the sole between the points h and i to overhang the other, as shown at Figs. 4 and 6, so as to form a projecting ledge k for the purposes hereinafter 95 described, or the said middle sole instead of being formed out of one piece, say, of leather, as above described, may be built up in, say, two (or more) layers or portions in a similar manner to heels of ordinary construction. A middle sole formed in two layers or portions (hereinafter termed "portions" and marked, respectively, c' and l') is shown at 100 Figs. 15 and 17. The portions c' and l' are

made of two different sizes, suitably sewed, cemented, screwed, or riveted together. The upper portion *c'* is larger than the lower portion *l'*, so that it may overhang the latter for 5 forming the projecting ledge *k*, while the smaller portion *l'* forms the recess *j*. The recess *g* is formed around the edge or perimeter of the fore part of the portion *c'*, as above described. Although it is preferred to form 10 the said middle sole of leather in the ordinary manner, yet I would have it understood that when preferred the portion *c'*, forming the herein-described projecting ledge *k*, may be made of or its edge may be incased in any 15 other suitable material, such as, say, metal or the like, while the smaller portion *l'* is made of leather, cork, or other like material. In one of the surfaces of the middle sole *c*, (shown at Figs. 4, 5, and 6,) or when the said 20 middle sole is built up in two or more portions, (shown at Figs. 15, 16, and 17,) then in the larger portion *c'* is cut or otherwise formed a longitudinal dovetailed recess *m*, which extends to a suitable distance under 25 the heel-retaining block, (shown at Figs. 4 and 5,) and it is employed for the purposes to be hereinafter described. In some cases, as at Figs. 15 and 16, the recess *m* is dispensed with. 30 On the same surface as that in which the recess *m* is formed, when such is used, is built and fixed, by sewing or nailing or riveting or cement, at a suitable distance from the rear of the middle sole what is termed a "heel-receiving" block, formed of, say, two layers 35 or "lifts" *n* and *o*, placed one upon the other, as at Figs. 4 and 15. Both layers are of similar shape to the heel *f*, but of different sizes. The layer *o* is the larger of the two layers, so 40 that its perimeter may overhang the smaller layer *n*, thereby forming the projecting ledge *p*, and also a recess *q* between the under surface of the layer *o* and surface of the middle sole or layer *c*. In the layer *n* at Fig. 7 is 45 cut or formed a longitudinal dovetailed or other recess *r* for receiving a portion of the outer sole *e*, to be hereinafter described. 50 The detachable and removable outer sole consists of a main portion *e*, shaped as shown at Figs. 9 and 20—that is to say, it is made of the same size and contour as and to cover the middle sole from its toe to the heel-retaining block before the portion forming the recess has been removed. The said outer sole *e* is provided with a tang or projection *s*, 55 adapted to fit into the recess *r* in the layer *n* of the heel-retaining block, and with the shoulders *t* and *u*, which are made to pass under the layer *o* (of the heel-retaining block) 60 into a recess, to be presently described, in the sliding heel *f*. Around the front or toe portion of the outer sole corresponding to and adapted to fit into the recesses *g* and *j* of the middle sole *c* is fixed, say, by sewing, nailing, riveting, cementing, screwing, or the like to its inner surface a flanged projection 65 consisting of a rim *v* made to project at or about a right angle to the said sole to form a recess *w* for receiving and inclosing the overhanging and projecting ledge *k* of the middle sole. A flange *x* is fixed to the upper edge of the rim *v*, so as to project inwardly and to fit into the rabbet or recess *j* when the outer sole is placed in position upon the middle sole *c*. The length of the rim *v* is determined 70 by the distance between the points *h* and *i*, while its breadth and thickness are made to correspond, respectively, with the width of the recess *g* and the thickness of the projecting ledge *k*. Further, the distance that the 75 flange *x* projects inwardly from the rim *v* is regulated by the width and depth of the rabbet *j*. By this means when the rim *v* and flange *x* are placed in position on the middle sole *c* they require to exactly fill the recess *g* and rabbet *j*, thereby replacing the portions 80 of the middle sole that have been removed at these points. 85 When the outer sole *e* is employed for the heavy class of boots, then it is preferred 90 (though not necessarily so) to fix to the same surface of the said sole as that to which the rim *v* and flange *x* are attached a longitudinal dovetail projection 2, Figs. 8 and 10, which is adapted to fit and slide freely in the recess *m*, formed in the middle sole *c*. The object 95 of this projection and recess is to insure of thick and heavy soles being retained in position and in contact with the inner sole, as well as to relieve the flange *x* and projecting ledge *k* of as much strain as possible; but for the lighter classes of boots the projection 2 and recess *m* may be dispensed with, as at Figs. 100 13 to 20, in which case the outer sole *e* and middle sole *c* are retained chiefly in position 105 and in contact by the flange *x* and projecting ledge *k*. 110 The detachable and removable heel is constructed in a similar manner to the outer sole *e*, and it is made of the same size and contour as the rear of the middle sole and to cover the same. It consists, namely, of a main portion *f*, made up of one, two, or more layers or lifts, a rim *y*, fixed by any of the herein-before-described means to one of the surfaces 115 of the said portion *f*, which receives and incloses the edge of layer *o* of the heel-retaining block, and an inwardly-projecting flange *z*, fixed to the said rim, and entering the recess *q* in the heel-retaining block. Recesses 11 120 are also formed by cutting away a portion of the ends of flange *z* at the breast portion thereof for receiving the shoulders *t* and *u* of the middle sole *c* and aid in retaining it in position. The length of the rim *y* requires to be such 125 that it will extend all around the heel from the breast on one side to the breast of the other side—that is, from shoulder *t* to shoulder *u*—while its thickness corresponds with that of the layer *o* and projecting ledge *p*. 130 The breadth of the flange *z* requires to be such that it will fill the space between the perimeter of the layer *n* and the outer contour of the middle sole *c* around the heel-re-

taining block, while its thickness is regulated by that of the layer *n*. By this means the rim *y* and flange *z* are made to fill up the spaces around the heel-retaining block.

5 3 is a screw of any suitable construction and is made to pass from the inside of the boot through the inner sole *b*, middle sole *c*, tang *s* of the outer sole *e* into the layer or layers *f* of the heel for retaining or locking 10 the detachable and removable sole and heel in position on the middle sole *c*, as shown at Figs. 1 and 13.

The welt *d* is sewed or otherwise attached to the middle sole *c* and extends around the heel 15 between the points *h* and *i*.

The said middle sole *c*, outer sole *e*, and heel *f*, having been constructed as herein described, are placed and fixed in position as follows: The upper *a*, having been lasted to the inner 20 sole *b* and the middle sole *c* fixed thereto by any ordinary means, it is then held with its sole uppermost, as at Figs. 1 and 13, when the outer sole *e* is made to slide from the toe portion of the lasted upper to its heel upon the 25 middle sole until its tang *s* and shoulders *t* and *u* have respectively passed into the recesses *q* and *r*, under layer *o*, and against the breast of the heel-retaining block. During the said sliding movement the flange *x* will 30 have entered the rabbet or recess *j* and the projecting ledge *k* have become inclosed within the recess *w* of the rim *v*. After this has been done the heel can then be placed in position by causing it to slide from the rear of 35 the upper to its toe, during which movement the overhanging projecting ledge *p* of layer *o* of the heel-retaining block will be made to enter its inclosing recess formed by the rim *y*, and the flange *z* simultaneously enters into 40 the recess *q*, while a portion of the shoulders *t* and *u* of the outer sole *e* enter the recess *l*. The screw 3 is then placed in position, as previously described, and the whole of the parts secured in position.

45 By means of the inclosing rims and projecting ledges and flanges being made to fit into and incase each other when in position the sole and heel of the boot present the same appearance as those of ordinary construction, 50 and as they become worn they can be readily removed and replaced with new ones without any danger of the boot being unduly strained

by the insertion of the repairer's last. The edges of the sole and heel can be pared and finished in the usual manner by ordinary means.

What I claim as my invention, and desire to secure by Letters Patent, is—

1. In a boot and shoe the combination of an upper lasted to the inner sole, a middle sole 60 fixed to said inner sole, said middle sole having a portion of its fore part removed and a rabbet formed in the recessed portion of said fore part to form a projecting ledge, a central longitudinal grooved recess formed in the opposite surface of the said sole to the rabbet, and a detachable and removable outer sole 65 adapted to slide into position on the middle sole and provided with a projecting rim, in-turned flange, and a central longitudinal projection, all arranged to fit into the said recesses and to inclose the projecting ledge of the said sole, substantially as set forth and as illustrated.

2. In a boot and shoe the combination of an 75 upper lasted to the inner sole, a middle sole fixed to said inner sole, said middle sole having a portion of its fore part removed and a rabbet formed in the recessed portion of said fore part to form a projecting ledge, a de- 80 tachable and removable outer sole adapted to slide into position on the middle sole and provided with a projecting rim, in-turned flange, all arranged to fit into the said recesses and to inclose the projecting ledge of 85 the said sole, a heel-retaining block provided with a recess and projecting ledge as described and fixed near the rear of the said middle sole, a detachable and removable heel adapted to slide into position on the middle 90 sole and having a projecting rim and in-turned flange adapted to fit into the said recess and to inclose the projecting ledge of said heel-retaining block and the means described for retaining the detachable and removable sole 95 and heel in position, all substantially as herein described and as illustrated.

In testimony whereof I have signed my name to this specification in the presence of two subscribing witnesses.

TOM LEADBEATER.
